SOUND RECORDING AND REPRODUCING SYSTEM

Clifford L. Price, Oakland, Calif.

Application January 10, 1944, Serial No. 517,762

6 Claims. (Cl. 179—100.3)

This invention, a sound recording and reproducing system, is an improvement over existent systems such as the molded plastic and sound-on-film types, in that the highest degree of fidelity is attainable with an absolute minimum in size, volume and weight of the recordings.

With the conventional sound-on-film method of recording and reproducing sound, about 60 or more feet of 35 mm. film, and corresponding lengths of 16 mm. and 8 mm. film is required to record and reproduce each minute of program. The decreased lengths with 16 mm. and 8 mm. film are not due to any desire or anticipation of reducing the length of the recording or sound track, but develops through a matter of necessity, the desire being merely to reduce the size of the frames which in turn requires that the portion of the sound track included in a 35 mm. frame must be reduced along with the picture to fit in the smaller frame. With my invention a one-minute program of equal fidelity is reproduced from only 2½ feet of film, and twenty-five or more recordings or different sound tracks can be recorded on an 8 mm. film.

Plastic records are bulky and heavy, very easily damaged, and deteriorate fairly rapidly with repeated playing, while with my type of recording, extremely light weight, minimum bulkiness, and freedom from damage and deterioration are prevalent.

With my invention, spiral recordings can be made on 35 mm. film to play for the same length of time as standard disc records. If desired, these spiral records can be produced in spaced relation on a continuous strip of 35 mm. film and thus used with suitable selecting mechanism in the reproducing unit, or the recordings may be separated into individual records.

The recordings are preferably reproduced from the original recording or matrix, to a scale conforming to the resolving power of the film to be used, and then preferably projected to a size about equal to that of the original record, with the enlarged image of the sound track in light and shadow intercepted by a suitable photo-cell, followed by suitable amplification and translation into sound.

The objects and advantages of the invention are as follows:

First, to provide a system of sound reproduction in which the greatest degree of fidelity it attainable.

Second, to provide a system in which the recordings are of minimum size and weight.

Third, to provide a system in which the re-

cordings are photographically formed from a matrix having a normal size sound track, on a relatively small area or length of film, to a greatly reduced scale.

Fourth, to provide a system in which an original sound track or matrix is made by conventional sound-on-film recording apparatus, and recordings made therefrom to a greatly reduced scale.

Fifth, to provide a system in which the recordings are produced from a normal sound track by photo-copying to a greatly reduced scale, on a transparent base photographic emulsion followed by suitable development.

Sixth, to provide a system in which sound is normally converted into photographic densities to form a sound track of normal size, and producing recordings for use by photographing said sound record or track to a scale established by the resolving power of the emulsion used.

Seventh, to reproduce sound from said recordings of greatly reduced scale by projecting a traveling image of the sound track through an optical system to a size approximating that of the original sound track, photometrically intercepting the enlarged light and shadow image, amplifying the effects of the intercepted light and shadow fluctuations, and translating the amplified fluctuations into sound waves.

Eighth, to provide a sound reproducing system in which sound waves are photographically microscopically recorded and projecting a light and shadow image of said sound waves to a greatly enlarged scale to form a sound track of light and shadow, intercepting the light and shadow sound track by photo-sensitive means, amplifying the relative fluctuations in current flow set up in the photo-sensitive means through variations in light intensities as the projected image travels across the photo-sensitive means, and translating the amplified fluctuations into sound waves.

Other objects and advantages of the invention will become apparent as the following description is read on the accompanying drawings, in which:

Fig. 1 is a fragmentary plan view of a matrix with a spiral sound track formed thereon through conventional sound-on-film recording means.

Fig. 2 is a full size plan view of one of the recordings as made from a spiral matrix, on 35 mm. film, with the sound track only illustratively indicated on a greatly enlarged scale.

Fig. 3 is a side elevation of the reproducing unit for the spiral form of sound track, and is partly shown in section.

Fig. 4 is a front elevation of Fig. 3.

Fig. 5 is a plan view of the recording holder

and rotating means for the spiral type of recording, together with the optical system for projecting the light and shadow image of the sound track to the photo-cell.

Fig. 6 is a section taken on line 8-8 of Fig. 5. Fig. 7 is a modification of the matrix fragmentarily shown, and indicating a multiplicity of sound tracks in parallel.

Fig. 8 illustrates a modification of the feeding means, for feeding lineal or ribbon recordings, and includes means for adjusting the recording transversely for selection of the respective sound tracks for different programs, and is taken on a line 8-8 of Fig. 9.

Fig. 9 is a front elevation of the reproducing unit for ribbon type recordings.

Fig. 10 is a side elevation of Fig. 9.

Fig. 11 is a fragmentary view of an 8 mm. ribbon type recording, with a plurality of sound tracks in parallel.

Fig. 12 diagrammatically illustrates the method of copying ribbon matrices to a reduced scale in accordance with this invention.

The matrix Fig. 1, is preferably formed on a circular disc of moisture proof base supported photographic emulsion, and may be either, developing paper, plate, or film; plate or film being preferable because paper would necessitate copying to the reduced size by reflection, while a plate or film is correctly copied through transmission.

During the recording process, which is carried out by conventional sound-on-film recording equipment, the film, instead of being fed lineally, is fed spirally through simultaneous rotation and diametric adjustment, so that the sound track 10 will be formed as a continuous spiral from the periphery 11 toward the axis 12, with a clear space 13 left between convolutions. Processing is carried out by any of the conventional processes, the circular form permitting rotational agitation in the processing solutions, thereby avoiding edge wash as would occur with rectangular sheets, assuring uniformity in processing even with variable density types of sound tracks.

The correctly processed matrix is copied through conventional methods, such as a reducing camera, on a small section or short length of film having very high resolving power, such as Micro-film or Graticular film, with a two-foot diameter matrix readily reduceable to a diameter of about 24 mm., (the space 14 between the sprocket holes 15 in 35 mm. film), as shown in Fig. 2 though other sizes of film can be used, and the recording made larger or smaller, as may be desired or required. There is one distinct advantage in having the recording as small as possible; it obviates the necessity for a comparatively long focus lens, or for a transverse feed for a short focus lens, for the reproducing system.

In making these miniature recordings, the film can be punched at some point such as 16 for indexing, through the medium of the conventional pressure back on the camera which can easily be provided with a suitable punch and die. A suitable title or identifying number 17 can also be applied to the clear ends or sides, with the title or number simultaneously indicating by its correct reading position the correct placement of the recording in the reproducing unit. Such equipment and devices are well known in the art and are therefore believed to require no description.

In connection with the production of these miniature or microscopic recordings, it might

be mentioned that Micro-film is capable of resolving about 230 lines per mm., while Graticular film is capable of resolving about 500 lines per mm. The resolving powers of these films are therefore respectively about 4μ and 2μ . Thus, if the matrix is 24 inches in diameter with the pitch P of the spirals equal to $\frac{1}{8}$ inch, the pitch p of the spirals on a 35 mm. reduced recording will be about .005 inch or 127μ , with the sound track having a transverse width of about .0025 inch or 63μ , and the space between the spirals also .0025 inch or 63μ . This is equal to about sixteen times the resolving power of Micro-film, and thirty-two times that of Graticular film, a very ample margin.

With conventional recording and reproducing methods, each minute of program requires at least 60 feet of 35 mm. film, and corresponding lengths of 16 mm. and 8 mm. film, though, as previously stated, this reduction is made to 16 or 8 mm. film only as a matter of necessity, to condense the relative proportion of sound track within the space occupied by one frame or picture. With my system only $2\frac{1}{2}$ feet of Graticular film, or 5 feet of Micro-film, is required for a recording of similar frequency and fidelity, and it is easily possible to record twenty-five sound tracks in parallel on a strip of 8 mm. film, with only $37\frac{1}{2}$ feet being required for fifteen-minute recordings. The matrix can be made on a comparatively wide ribbon, three or four inches, if a large number of sound tracks are to be produced on the same miniature recording. However, from one to eight sound tracks can be recorded on 35 mm. film, and several of these can be recorded to the reduced scale on a single strip of 8 mm. film. Obviously, this system is not limited to 8 mm. film. Any desired size can be used.

The reproducing unit for the spiral type of recording is illustrated in its simplest form as comprising an enlarging unit together with suitable feeding means, which broad statement applies equally to the lineal or ribbon type of recording.

A projection lamp 18 is housed in a suitable lamp housing 19 which at its lower end has a very narrow slit 20 of sufficient length to extend over the cumulative recorded width of the series of parallel recordings, or for spiral recordings, across the radial width of the spirals which would be somewhat less than the radius of the recording for spiral sound tracks, and which in the case of 35 mm. recordings 21 would be about 1 cm., as there would be no sound track close to the axis. It is understood that a suitable condenser system or diffusion screen, or both, may be incorporated in the illuminating unit.

The holder and turntable for the spiral type of recording consists of a gear 22 having an axial passage 23 equal in diameter to the diameter of the recording, and has combined locators and spring clips 24 with the locating shoulders spaced apart a distance exactly equal to the width of the recording blank. An indexing button 25 is receivable in the hole 16 for accurately locating the recording lengthwise; the recording being slipped under the clips and pushed forward until the hole snaps over the button 25.

Projecting from the underside of this gear is a bearing collar 27 which rotatably fits in a gib bearing 28 which is integral with the arm 29 which extends from the shaft bearing 30 which is mounted on the upright 31. This bearing 28 has a lens barrel 32 located eccentrically and in registry with the light beam slit 20, and has a suitable lens combination 33 mounted in the lens

barrel. The projection lamp housing is mounted in a head 34 which is hinged at 35 so that it can conveniently be tilted out of the way to provide access to the recording holder.

Mounted in bearings 36 on the base 37 is a feed screw 38, and in parallel relation to the feed screw is a guide rod 39 on which is slidably mounted one end of a support 40 which has a half nut 41 formed at its other end to threadedly cooperate with the screw 38, and a handle 42 projects beyond the half nut for manual lifting of the half nut out of engagement with the screw 38 so that the support can be slidably returned to its starting position.

Mounted on the support 40 is a photo-cell unit 43 which intercepts a predetermined area of one spiral of projected rays such as 44 of the projected light and shadow image of the sound track on the recording, and transmits the results of fluctuations in light intensity or volume of the traveling projected sound track to a suitable amplifier 45 and thence to a sound translating device 46; the structures, functions, and operations of which are well known in the art and are conventional equipment.

The screw 38 may have a pitch equal to the pitch of the projected spirals, under which conditions the rotational speeds of the screw 38 and the recording holder 22 are equal, being driven by a very slow speed motor 47, or by a motor with suitable speed reducer. As shown, the screw is driven direct, while the recording holder is driven from the screw through the miter gears 48, shaft 49, and gear 50.

Obviously, the shorter the focal length of the lens 33, the less will be the distance between the recording 21 and the photo-cell 43. Since the light passes only through an extremely narrow slit, the focal length of the lens can be about equal to the length of the slit, in the case of 35 mm. film about 10 to 12 mm., with the distance from lens to photo-cell being anywhere from five to thirty-five focal lengths.

In making the matrix, the blank can be rotated similarly to that of the recording in the reproducing unit just described, coupled with a diametric feed to produce the spiral sound track, and with the recording beam of vibratory mirror in a definite and fixed location.

For ribbon recordings on 8, 16 or 35 mm. films, the matrix may be made as illustrated in Fig. 7, with one, or with a plurality of different sound tracks in parallel. This matrix is then copied to a reduced scale indicated in Fig. 11 as diagrammatically illustrated in Fig. 12, in which sets 51 and 52 of suitable feed rollers are provided for feeding the respective matrix 53 and ribbon 54 of film on which the recording is to be made.

A suitable projection lamp 55 illuminates the sound track on the matrix through a slit 56 formed in the pressure plate 57, the illuminated image of which is projected by the lens 58 through the slit 59 in the pressure plate 60 to the photo-sensitive emulsion 54 to a greatly reduced scale; the roller 51' being driven by suitable driving means, and in turn driving the roller 52' at a greatly reduced speed as indicated by the belt 61 and sheaves 62 and 63.

The reproducing unit for ribbon type recordings consists of a feed plate or platen 64 which has a slit 65 through which the image of the sound track 66 is projected through the lens 67 to the interceptor or photo-cell 68 as indicated at 69; the sound track, lens, and interceptor being

in perfect alignment and the lens properly focused.

This feed plate is slidably mounted in a support 70 as indicated at 71 and is transversely adjustable to bring the respective sound tracks, such as 66 and 72 in perfect registry with the axis of the lens and with the interceptor, by means of spaced screws 73 which are rotatable in bearings 74 on the support 70, and threadedly operable in threaded passages formed in the upright 75 on the platen 64. These two screws are coupled together for synchronous operation as indicated at 76, by means of the knob or dial 77 which is provided with calibrations 78 for coordination with the pointer 79. The recording 80 is perfectly aligned between the shoulders 81 and 82, 81 being formed as a slot having a top wall functioning as a hold-down for the one edge of the recording, while the other side is held down and fed by suitable means such as the toothed rollers 83 and 84 and encompassing pierced band 85, the teeth on the rollers being sufficiently long to pass through the band and engage the sprocket perforations 86 in the ribbon for positive driving of the recording. The respective rollers 83 and 84 are fixed on the respective shafts 87 and 88 which are rotatable in bearings 89 and 90 integral with the plate 64. The shaft 87 is slideable and non-rotatable in a sleeve 91 which is rotatable in a bearing 92 integral with the support 70.

A suitable drive is provided and as illustrated consists of a sheave 93 which is fixed on the outer end of the sleeve 91 and driven by a belt 94 by means of a sheave 95 mounted on the shaft of a very slow speed motor 96, or, by means of a motor with a suitable reduction gear.

A projection lamp 18 is mounted in a suitable lamp housing 19, and the slit 20 is formed in a neck 21 which is slideable on the lamp housing and adjustable with the feed plate, being secured thereto.

The interceptor or photo-cell is connected in circuit with a suitable amplifier 45 and sound translating unit 46.

The support 70 is integral with a standard 98 and integral base 99 on which the interceptor is mounted in a fixed position.

As indicated at 68, the sound track is enlarged into a traveling light and shadow image, to a size preferably about equal to that of the originally recorded sound track at the point 100 where the light and shadow image is intercepted by the photo-cell. The speed of travel and the area of the intercepted light and shadow image is therefore approximately equal to that of the original recording.

The correct speed of travel of the recording is governed preferably by the resolving power of the emulsion used. Graticular film is capable of resolving about 500 lines per mm. which is equivalent to about 12,750 lines per inch. On this basis, the correct speed for a 6000 cycle sound track would be about 12 mm. or approximately $\frac{1}{2}$ inch per second, while for extreme fidelity at 10,000 cycles per second the correct speed would be about 20 mm. or approximately $\frac{1}{4}$ inch per second. Micro-file film is capable of resolving about 230 lines per mm., which is equivalent to about 5,850 lines per inch. On the basis of 6000 cycles per second the correct speed would be about 26 mm. or approximately one inch per second, and for 10,000 cycles per second, about 44 mm. or approximately $1\frac{1}{4}$ inches per second.

The reduction from the matrix for Graticular

film would be on the order of 24:1 to 36:1, and for Micro-file film about 12:1 to 18:1, though any desired reduction not exceeding the previous maximums could be used. Speeds and reductions for other types of emulsions would be proportionate to their respective resolving powers.

In the case of Graticular film reduced to $\frac{1}{4}$ of the original matrix, the distance between the lens 32 or 67 and the interceptor 43 or 68 should preferably be made equal to twenty-five focal lengths. In other words, the projection distance should be equal to the ratio of reduction plus one, multiplied by the focal length of the lens. However, this value may be increased or decreased as desired.

It will be noted that if the original sound track is recorded at a lineal speed of 30 feet per second, the recording made with a reduction of 24, then enlarged 24 times, the traveling light and shadow image of the sound track at the point of interception will have the same lineal speed as the original, thirty feet per second.

I claim:

1. Sound reproducing apparatus comprising: a first support; a lens mounted on one side of said support and a source of projection illumination mounted on the other side; means rotatably mounted on said first support between said lens and said source of projection illumination for supporting a disc-type photographic recording in the focal plane of said lens; a second support in spaced relation to said first support; a photo-cell located in the object plane of said lens and radially adjustable on said second support; and driving means for driving said means rotatably mounted at uniform speed and simultaneously radially adjusting said photo-cell at a speed coordinated to the speed of radial travel of the projected image of the sound track on the disc-type recording.

2. A structure as defined in claim 1; said means rotatably mounted comprising a ring gear peripherally supported and having means for peripherally securing a disc-type recording thereon; said driving means for radially adjusting said photo-cell comprising a screw and a guide bar mounted on said second support in parallel and a support slidable on said guide bar and having a half-nut cooperative with said screw, and an operative connection between said screw and said driving means for rotating said screw; said photo-cell being mounted on said support slidable.

3. Sound reproducing apparatus comprising: a lens; means for supporting and rotating a disc-type photographic sound recording having a spiral sound track, in the focal plane of said lens, and means for illuminating said record; a photo-cell radially adjustable relative to the axis of a projected image of said sound recording and

located in the object plane of said lens; driving means for rotating said means for supporting, and for radially adjusting said photo-cell in coordination with the speed of radial travel of the projected image of the sound track, and amplifying and sound translating means in circuit with said photo-cell.

4. A structure as defined in claim 3; said means for supporting comprising; a gear member which is light-transmitting throughout the area of the sound track on the recording to permit passage of light therethrough to said lens; said means for radially adjusting said photo-cell comprising a guide bar and a screw mounted in parallel, and a support slidable on said bar and having a half-nut for threaded cooperation with said screw for adjusting and for convenient manual return of said support slidable to a starting position, a gear for said screw; said driving means including a gear connection to said gear member and to said gear for said screw.

5. Sound reproducing apparatus for disc-type photographic recordings having a spiral sound track comprising; a lens; rotatable supporting means for supporting a recording in the focal plane of said lens and permitting passage of light therethrough to said lens, and illuminating means for said recording; a photocell located in the object plane of said lens, and driving means for said rotatable supporting means and for simultaneously adjusting said photo-cell in conformity with the speed of radial travel of the projected image of the sound track of the recording, and including means for manual return of said photo-cell to starting position at will; and amplifying and sound translating means in circuit with said photo-cell.

6. Sound reproducing apparatus for disc-type photographic recordings having a spiral sound track comprising; a first support having a lens mounted on one side and a source of illumination on the other side; a gear rotatably mounted between said lens and said source of illumination and forming means for peripherally supporting a recording while permitting passage of light through the recorded area to said lens; a base; a slide bar and a screw mounted on said base in parallel and radially relative to the axis of said gear; a second support slidable on said bar and threadedly cooperative with said screw and manually disengageable from said screw, and a photo-cell mounted on said second support and located in the object plane of said lens; means for driving said gear at uniform speed and for driving said screw to adjust said photo-cell at a speed equal to the radial travel of the projected image of the spiral sound track; and an amplifying and sound translating circuit for said photo-cell.

CLIFFORD L. PRICE.
